UNITED STATES PATENT OFFICE.

JOHN L. G. DYKES, OF CHICAGO, ILLINOIS.

AUXILIARY SOLE FOR FOOTWEAR.

Application filed April 23, 1926. Serial No. 104,083.

My present invention has relation to the provision of auxiliary soles for footwear, which may be readily attached to or detached from the soles of shoes or other foot-
 5 wear, when occasion may require, and when attached will be dependably retained in assembly with the footwear for the purposes of the general or special service for which the particular auxiliary sole is designed.
 10 The desirability of such an auxiliary sole has already been appreciated in connection with protecting the footwear from water and a special variety of rubber overshoe, called a "toe rubber," has been designed.
 15 which consists of a sole and a very much reduced vamp and upper heel portion for engaging the edge of the sole and the bulge of the vamp, which vamp and upper heel portion is carried rearwardly of the sole in
 20 a loop for engaging the footwear at or adjacent the ankle. Such special rubber overshoes, however, have hitherto been regarded as only suitable for light service as the reduced vamp and its direct extension around
 25 the posterior portion of the foot does not secure a sufficiently dependable assembly with the footwear to withstand anything but light service.

It will be at once appreciated that if an auxiliary sole can be dependably, attachably and detachably secured to footwear its capabilities and uses will be greatly extended over the uses of the mere overshoe and its special form the "toe rubber." For instance,
 30 such auxiliary sole may be employed for increasing the service and useful life of the shoe itself; it may be employed for emergency repairs to the sole; and by providing it with suitable configuration it may be re-
 35 movably attached for temporarily securing all of the functions for which hobs, bosses and cleats are now permanently secured directly to the sole.

I attain the provision of a dependably attachable and detachable auxiliary sole for footwear by means of the construction illustrated in the accompanying drawing, in which—

Fig. 1 is a perspective illustration of a portion of a shoe with my invention in assembly therewith;

Fig. 2 is a perspective of the form of my invention shown in Fig. 1 separate from a shoe;

Fig. 3 is a bottom plan of a shoe, such as is shown in Fig. 1, showing the manner of

assembly of my auxiliary sole therewith, a slightly modified manner of assembly being shown in dotted lines;

Fig. 4 is a cross-section through the sole 60 of the footwear and auxiliary sole in assembly on line 4—4 of Fig. 3;

Fig. 5 is a central longitudinal section on line 5—5 of Fig. 3.

My auxiliary sole is designed for assembly and use with those varieties of footwear which include a sole and a vamp having a groove, depression or channel at the line of junction between these parts. The sole proper, 10, of my auxiliary sole has a plan 65 or outline which registers with or nearly approximates the outline of the sole of the footwear with which it is assembled from the toe rearwardly to points 11 on each edge somewhat posterior to the widest portion of 70 the sole, from which points runs a truncated triangular apron or extension, 12, to just in front of the heel of the footwear. As my auxiliary sole covers only the sole of the footwear there are no objections whatever to 75 making it of material impervious to air as little or no ventilation reaches the foot through the sole of the footwear. For moisture insulation and general uses I therefore 80 form the portion of the sole above described 85 of vulcanized rubber suitably reinforced with fabric as is the present best practice in fabricating rubber overshoes. However, it should be clearly understood that such a method of fabrication of the sole proper is 90 by no means necessary to the practice of my invention and that any suitable material or materials and method of fabrication may be employed, the only limitation being that the sole proper, when formed, must be capable 95 of incorporation or vulcanization with the remainder of the structure to be now described.

Running around the edge of the forward portion of the sole proper between the points 100 11, 11, is a right angular or upstanding flange or web, 13, of a height or width approximately that of the sole of the footwear with which the auxiliary sole is to be assembled, and of a thickness and composition 105 such as to secure relatively greater elasticity than the body of the sole proper. Vulcanized in or to the top, or the inner face at the top edge, of the flange or web 13 is a constricting element, 14, which extends rearwardly of the ends of the flange or web, and is of such a length or extent as to form a

loop, 15, capable of crossing over or being twisted beneath the apron 12, and including or surrounding the heel, 16, of the footwear and seating in the depression or groove, 17, between the sole, 18, and vamp and heel portion of the upper, 19, of the footwear. The provision and location of the element 14, or its equivalent, with relation to the other parts of the auxiliary sole and the parts of 10 the footwear with which it is assembled is of the gist of my invention, and its function is to constrict and secure the top of the flange or web 13 within the depression or groove 17 between the sole and vamp of 15 the footwear as well as to support and hold the apron 12 against the lower surface of the arch of the sole of the footwear. The crossing or twisting of the rearwardly looped portion of the constricting element 14 beneath the arch of the sole of the footwear not only greatly improves the gripping capabilities of this element by holding it tightly to the widest portions of the sole and forward corners of the heel, but also, by means of 20 25 a greater or less amount of twist, affords facilities for a nice regulation of the desired degree of constriction. The element 14 may be formed of vulcanized cord having some inherent elasticity, or of metallic wire covered with vulcanized rubber, which has little or no inherent elasticity, as the soles of all footwear may be slightly flexed or curved downwardly, to a position they would never assume in service which shortens the distance between the extremities of the sole of 30 35

the footwear and permits the element 14 to be put in position.

Having described my invention, what I claim as new and desire to secure by Letters Patent is:—

1. In combination with footwear including a sole and an upper having a depression or groove at their juncture, an auxiliary sole comprising a sole substantially registering with the sole of said footwear, an upstanding flange extending around the forward edge of said sole between points posterior of the widest portion thereof, and means constricting the upper edge of said flange within said groove of said footwear, consisting of a continuous, uniform vulcanized, reinforced cord or bead running along the upper edge of said flange and extending rearwardly thereof and forming a loop twisted beneath the arch and entering the groove between the heel and upper of said footwear. 50 55

2. An auxiliary sole for footwear comprising a sole, an upstanding flange extending around the forward edge of said sole between points posterior of the widest portion thereof, and means for constricting the upper edge of said flange when in assembly with footwear, consisting of an endless, uniform, vulcanized, reinforced cord or bead running along the upper edge of said flange and extending rearwardly thereof and adapted to be twisted beneath the arch and entering the groove between the heel and upper of said footwear. 60 65
